Application July 26, 1934, Serial No. 737,050

5 Claims.

(Cl. 2—14)

This invention relates to improvements in goggles the main object of which is to insure against fogging or breaking of the lenses in industrial service or the like, and it consists in the improved construction hereinafter fully set forth in connection with the accompanying drawing illustrating preferred embodiment thereof, with the novel features specifically defined in the subjoined claims.

- 10 Heretofore provision has been made for ventilating the lens-receiving chambers of goggles by means of guarded air inlets through the lateral walls of the chambers, and for guarding against breakage of the lenses by providing a 15 resilient seating for the lens intended to absorb the shock of lens-contacting foreign matter. This complete invention provides for simultaneously securing both these objects by a novel and advantageous construction involving provision for a ventilating inflow of air from the 20 front of the goggles through a circular series of channels surrounding each lens edge, with radial diverting of such inflow at the rear of the lenses by means of a ventilating ring adapted to 25 serve also as a shock absorbing device.

In all cases where this latter purpose is to be accomplished we have found it important for the avoidance of lens breakage by exterior shocks, that this shock absorbing ring should not only 30 be adapted to absorb a normally disrupting shock by a form-distorting yield thereof, but that any rebound action of the distorted ring should be avoided as actually tending to cause breakage of the lens because of sudden reversal of the strain 35 upon it. To this end we specifically provide for preventing such rebound action by making the ring practically non-elastic, preferably by forming it of a non-elastic pressure-distortable material; the fact that this novel quality calls for 40 replacing of it by a new ring after it has been subjected to a distorting shock being relatively unimportant. Though this specific non-elastic shock-absorbing ring is advantageously employed 45 in connection with the ventilating functioning provided for in my complete invention set forth, it may also be employed independently of the latter.

Fig. 1 is a sectional view indicating the application of our invention to one eye cup of a known type of goggles in which the lens-receiving chamber is formed in the forward portion of the cup.

Fig. 2 is a similar view showing our invention applied to another known type of eye-cup goggles 55 in which the lens-receiving chamber is provided

in a separate screw-cap clampingly secured to the main cup.

Fig. 3 is a front view clearly showing the arrangement of air-inlet channels around the edge of the lens.

Fig. 4 is a separate plan view of the preferred form of ventilating ring indicated in both Figs. 1 and 2; with Fig. 5 showing a cross-sectional view thereof.

Fig. 6 is a similar cross-sectional view indicating a simple modification thereof, in which the shock-absorbing function involves non-resilient compression of the ring material as indicated in Fig. 7.

Fig. 8 is a separate view of the interior lens 15 clamping ring shown in the Fig. 1 embodiment.

Referring to the drawing, it will be understood that whether the lens-receiving chamber 10 is formed in the main framing 11 of the goggles as in Fig. 1, or in the lens-clamping screw cap 12 shown in Fig. 2, the lens is seated against an outer circular flange 14 by screw pressure operating through the interposed ventilating ring 16. This clamping pressure is provided in the Fig. 2 construction by merely screwing on the cap 12 to 25 seat the ring 16 against an inner offset 20; while in the Fig. 1 construction we employ an interiorly located screw ring 22, engaging an interior screw-threading 24 in the lens-receiving chamber 10, to 30 fixedly set the interposed ring 16.

To most satisfactorily secure the ventilating of the lens-receiving chamber 10, as is required particularly for freeing the lenses from objectionable moisture or fogging, we provide for an inflow of air around the edge of each lens from 35 the front, by means of a circular series of air-channels 30, formed in the wall of the chamber 10 with free front inlets 32 and radially directed outlets 34 to said chamber, rearward of the lens. The ventilating ring 16, which is held in the zone 40 of the outlets 34 and the inner lens face, is shaped to provide restricted passage ways 40, 40 through it to the chamber 10, for ventilation; these ways being preferably provided by means of spaced and relatively staggered contact projections 42, 45 42 upon the upper and lower surfaces of the thin ring band 41. In the slightly modified ring construction indicated in Fig. 6 these contact projections 42 are provided only upon one face thereof, and it will be readily understood that 50 other equivalent ring constructions may be employed to provide for such radial inflow of air to the chamber, with or without the capacity for absorbing lens shocks which is inherent in our improved ring as set forth.

The radial inflow of air to the lens chamber through the air ways in ring 16, comes directly from the front of the goggles through the circular series of channels and insures ample ventilation and a practically uniform temperature of the outer and inner faces of the lenses with certain avoidance of fogging. This occurs irrespective of the coincident functioning of the ring 16 as a shock-absorber, though such functioning is naturally incidental to the ventilating structure of the ring and commonly called for in industrial service involving the related danger of fogging. In the ring construction shown in Fig. 5 the thin ring band 41 will yield in form, to any undue shock upon the lens; whether resiliently or not depending essentially upon the character of the material employed. While with the modified construction indicated in Fig. 6 there can be no yielding to lens shocks, and consequently no shock absorbing utility, unless a material is employed which is especially adapted to such functioning because of non-resilient compressibility which enables the maximum thickness of the ring, through the knob projections 42, to be reduced as indicated in Fig. 7. Such required compressibility is simply and satisfactorily provided for by making the projections 42 readily pressable into the plane of the ring band as indicated, with no resulting rebound to strain the lens after absorption of a shock.

When thus compressed to advantageously absorb an accidental lens shock without rebound action, replacement of the ring is called for, but in any case its required functioning in the ventilation of the lens-holding chamber, is normally effected with insurance against fogging of the lens.

The invention as fully set forth in its preferred embodiments, may obviously be modified within the spirit of the invention as defined in the appended claims.

What we claim is:

1. In goggles having a lens-holding chamber, lens-clamping means comprising an interposed compressible non-resilient ring arranged in clamping contact with the inner surface of the lens and shaped to operate as a non-rebound lens-shock absorber.

2. In goggles having a lens-holding chamber, lens-clamping means comprising an interposed ring arranged in clamping contact with the inner surface of the lens, said ring having spaced non-resilient projections on its opposite faces arranged in staggered relation and adapted to normally space said lens from its seat and to non-reboundingly crush under a lens shock. 5

3. A goggle framing for clampingly holding a lens, comprising a fluted outer flange having 10 spaced circumferential contacts with a lens edge and intervening non-contacting recesses forming a series of open front rearwardly directed ventilating channels surrounding said lens, and lens clamping means movable relatively to said 15 outer flange and comprising a lens seating ring having inner lens face contacting non-resilient projections adapted to normally space said lens from its seat to form air channels communicating with said open front ventilating channels; 20 said non-resilient ring projections being adapted to non-rebounding crush under a lens shock.

4. A goggle framing for clampingly holding a lens, comprising a seating ring having spaced contacts with the inner face of a lens, and an outer 25 flange movable relatively to said ring and having spaced circumferential contacts with a lens edge and intervening radially projected flutings forming a series of open front rearwardly directed ventilating channels surrounding said lens edge 30 rearward of the outer surface of said lens and arranged to deliver rearward of the inner surface of the latter.

5. A goggle framing for clampingly holding a lens, comprising a seating ring having spaced 35 contacts with the inner surface of a lens, and an outer flange movable relatively to said ring and adapted to engage a lens edge rearward of its outer surface, said flange wall having a circular series of axially directed conduits forming open 40 front ventilating air channels surrounding said lens and adapted to deliver to the rear of said lens between the spaced contacts of said lens seating ring.
